o-PHENYLENE-BIS (TRINITROETHYLAMINE)
Robert H. Saunders, West Chester, Pa., assignor, by
mesne assignments, to the United States of America
as represented by the Secretary of the Navy
No Drawing. Filed Feb. 28, 1952, Ser. No. 274,074
5 1 Claim. (Cl. 260—577)

This invention relates to a new explosive compound, *o*-phenylene-bis (trinitroethylamine).

The new compound of the invention is an orange colored solid which is moderately stable at room temperatures.

It has properties making its utility as an explosive feasible, having an oxygen balance within permissible limits and an impact sensitivity in the range of that of picric acid.

The compound may be prepared by the condensation of *o*-phenylenediamine and trinitroethanol.

It is an object of the invention to provide a new explosive compound, *o*-phenylene-bis (trinitroethylamine).

The invention is illustrated by the following example, but it is not limited thereto:

.5 gram of trinitroethanol dissolved in methanol was added to .15 gram of *o*-phenylenediamine, also dissolved 25 in methanol. The mixture was chilled and the product precipitated by dropwise addition of water.

2

The compound was found to have the following formula:

10 The percentage composition calculated for $C_{10}H_{10}N_8O_{12}$ is 27.6 percent carbon, 2.3 percent hydrogen, 25.8 percent nitrogen and the remainder oxygen. Analysis of the compound gave, 31.5 percent carbon, 2.2 percent hydrogen and 25.8 percent nitrogen.

The new compound has an oxygen balance of —48. Its melting point is 70° centigrade. It has an impact sensitivity of 65 as determined by the Bureau of Mines impact machine, this figure being the distance in centimeters a 2 kilogram weight is required to fall in order to produce 50 percent shots.

It is thus seen from the above that there has been provided a new compound having properties making its utility as an explosive feasible.

What is claimed is:

o-Phenylene-bis (trinitroethylamine).
